UNITED STATES PATENT OFFICE.

THOMAS B. LASHAR, OF BRIDGEPORT, CONNECTICUT, ASSIGNOR TO INTERNATIONAL SILVER COMPANY, OF MERIDEN, CONNECTICUT, A CORPORATION OF NEW JERSEY.

DESIGN FOR A FORK, SPOON, OR SIMILAR ARTICLE.

45,195.

Specification for Design.

Patented Feb. 3, 1914.

Application filed October 28, 1913. Serial No. 797,911. Term of patent 7 years.

To all whom it may concern:

Be it known that I, THOMAS B. LASHAR, a citizen of the United States, residing at Bridgeport, county of Fairfield, State of Connecticut, have invented a new, original, and ornamental Design for Forks, Spoons, or Similar Articles, of which the following is a specification, reference being had to the accompanying drawing, forming part thereof.

The figure is a perspective of a fork embodying my novel design.

I claim:

The ornamental design for a fork, spoon or similar article, as shown.

THOMAS B. LASHAR.

Witnesses:

W.M. B. GRIFFIN,
GEO. T. KEATING.
